UNITED STATES PATENT OFFICE.

ADOLPH F. MEYER, OF ST. PAUL, MINNESOTA.

GOVERNOR.

Application filed March 29, 1920. Serial No. 369,604.

To all whom it may concern:

Be it known that I, ADOLPH F. MEYER, a citizen of the United States, resident of St. Paul, in the county of Ramsey and State 5 of Minnesota, have invented certain new and useful Improvements in Governors, of which the following is a specification.

This invention relates to a new and improved governor for the control of fluid flow and pressure. It is particularly adapted 10 for use as a means for the automatic maintenance of a desired speed of rotation of a driven member working under a friction load produced by fluid pressure. This governor is capable of a wide variety of uses 15 in which a sensitive and responsive automatic control of fluid pressure and flow is desired. In the selected embodiment of the invention herein disclosed, this novel governor is shown as adapted for use in the wood-pulp making art. It is particularly 20 adapted for use in connection with the well-known hydraulic turbine driven grindstones used for the production of wood-pulp. 25 In this art, as at present practiced, turbo-grinders are employed which have a plurality of what are termed pockets into which wood blocks are placed and are pressed by hydraulic means against the face of the rotating 30 grindstones. At present when the blocks in one pocket are completely ground or the pocket is pulled off for refilling with wood, the normal friction load on the turbo-grinder is resultantly lessened and the turbo-grinder speeds up, causing a loss of power 35 through reduced efficiency of the hydraulic turbine. In fact the speed of the turbo-grinders at present is continually varying as the friction load changes with the number 40 of pockets in use, the size and character of wood ground and the arching and binding of the wood in the pockets. By means of the invention here disclosed it is possible to maintain any desired speed of rotation 45 of the turbo-grinder and thus to prevent loss of power.

This novel and improved governor is entirely automatic in action. It always increases the pressure with the least increase 50 in speed of the turbo-grinder, and decreases it with the least decrease in speed. The forces employed in the device are in equilibrium, that is, in a state of rest, only when

the speed is normal. In consequence, it is possible to make the present governor as 55 sensitive as practical considerations dictate.

In view of the large amount of power applied to the turbo-grinder shaft, and the small fly-wheel effect secured from the turbine-runners and the grindstones themselves, 60 a condition is imposed which makes good governing an extremely difficult operation. Large speed variations occur normally in from one to two seconds, varying with conditions in individual mills. To help overcome any existing tendency towards "hunting" 65 an adjustable by-pass has been provided by means of which a steady friction load is applied to the grindstones irrespective of the action of the governor valve. In 70 other words, good governing is accomplished through the employment of a practically uniform resistance to flow through the by-pass, plus a variable resistance applied through the governor valves, the result of course being a variable pressure in 75 the grinder pockets as demanded by the conditions prevailing. In this way an extremely sensitive governor is provided that acts instantaneously, anticipates large speed 80 changes by its rapid motion, and thus produces sensibly constant speed of rotation of the turbo-grinder.

An object of the invention, therefore, is to provide an improved device for controlling fluid pressure. 85

A more specific object is to provide a means for the automatic maintenance of a desired speed of rotation of a driven member working under a friction load produced 90 by fluid pressure.

Other objects of the invention will more fully appear from the following description and the accompanying drawings and will be pointed out in the annexed claims. 95

In the accompanying drawings, there has been disclosed a structure designed to carry out the objects of the invention, but it is to be understood that the invention is not to be confined to the exact features shown, as various changes may be made within the scope of the claims which follow. 100

In the drawings:

Figure 1 is a vertical sectional view through the valve structure, with the valve 105 in the automatic stop position;

Figure 2 is a section on the line 2—2 of Figure 1, with the valve in the operating position;

5 Figure 3 is a section on the line 3—3 of Figure 2;

Figure 4 is a section on the line 4—4 of Figure 1;

Figure 5 is a diagrammatic view of the structure combined with a grinder.

10 In the preferred embodiment of this invention this means for the automatic maintenance of a desired speed of rotation, is shown in connection with a driven member such as a grindstone. A plurality of these 15 grindstones are usually mounted upon and rotated by a driven shaft. An instrumentality is provided to press wood placed in pockets against the face of the grindstones, and usually consists of a piston having a 20 head movable in a cylinder. The opposite end of the piston is provided with a foot by means of which the wood is pressed against the grindstone face. It is to be understood that, not only may a plurality of these 25 grindstones be mounted upon a shaft, but each grindstone may be provided with more than one of these cylinders and piston devices for pressing the wood in the several pockets against the grindstone. The grind- 30 stone is thus operated under friction load induced by sticks of wood thus forcibly held against its peripheral surface.

It is customary in this art to drive these 35 grinders by hydraulic turbine means. Such turbo-grinders have an efficient speed of rotation for any given condition and it is for the maintenance of this efficient speed of rotation that the structure here disclosed is employed. It is also common in this art 40 to employ a fluid under pressure not only for the purpose of forcibly pressing the wood in the pockets against the grinder by means of the piston, but also to use this fluid pressure to force the piston head away from the 45 grindstone in order that the pockets may be refilled. It should be noted that the maintenance or governing of the speed of rotation of these turbo-grinders is effected by the maintenance of a uniform friction load. For 50 example, when one pocket is pulled off for refilling it is obvious that the grinder would tend to speed up due to lessened load, hence the pressure must be increased upon the other pistons. A complication arises in that 55 the amount of fluid, such as water, consumed in forcing the pistons in their normal working movement to maintain objects engaged with the grinder, is small; while the amount of water consumed upon abnormal move- 60 ment of each piston from or to its object-maintaining position is relatively large. These two factors have heretofore been insurmountable obstacles to the efficient speed governing of the grinders. The novel structure here disclosed employs two co-operat-

ing mechanisms, which control the pressure supplied to the pistons. One of the mechanisms is actuated by changes in the speed of rotation in the turbo-grinder and the other is actuated by changes in the flow 70 of water to the cylinders and pistons. Only the latter mechanism is directly actuated by the abnormal movement of the piston. The former is indirectly actuated if such abnormal movement causes speed changes. In 75 order to prevent speed changes it is highly desirable that increased flow resulting from abnormal movement shall not cause a pressure drop in the cylinders which are pressing wood against the grindstone. In other 80 words, variations in pressure resulting from variations in water flow through the supply pass must be prevented. This novel structure effects such result through the co-operation 85 of the two mechanisms.

85 The selected embodiment of this invention in combination with such a turbo-grinder is diagrammatically shown in Figure 5. The grindstone 1 is fast upon the turbine-driven shaft 2. A cylinder 3 is suitably mounted 90 adjacent the peripheral surfaces of the grindstone and bears therein a piston-head mounted upon the rod 5, the opposite end of which carries a foot 6, operating in the pocket 7 to press objects, such as blocks of 95 wood, against the surface of the grindstone, whereby the wood is ground into pulp. It is necessary for the purpose of disclosure of this invention only to show one cylinder and 100 pocket and grinder, but it should be noted that the grinders are usually employed in a series fast on the same driven shaft and, furthermore, that a plurality of similar pockets and wood-pressing means are used 105 in conjunction with each grinder.

105 A pass is provided which is adapted to supply a fluid, such as water, under pressure from a suitable source, to the wood-pressing cylinders. Herein such pass is shown as comprising a supply pipe 8 connected to a 110 suitable source of supply of water under pressure, and having the valve mechanism interposed in the supply pass between the pipe 8 and the pipe 9, which forms a continuation of the pass. This pipe 9 supplies the 115 water under pressure in accordance with usual practice to each of the different pocket cylinders. As shown in Figure 5, a passage 10 is shown as leading from the pipe 9. This 120 passage is provided with a two-way valve 11 diagrammatically represented, which is manually operable either to divert the water under pressure to one side of the piston head while permitting escape of any water on the other side of the head, or vice versa. In the 125 position shown in Figure 5, the valve is shown as turned to permit water under pressure through the passage 10 and port 12 to the upper face of the piston head 4 by which means the piston head 4 is gradually down- 130

wardly forced to maintain the wood in engagement with the grindstone. This movement is termed, for the sake of brevity, the normal movement. As the piston head 4 is 5 downwardly forced by means of pressure admitted to the upper portion of the cylinder through the port 12, any water in the lower portion of the cylinder may escape through the port 13 by way of the two-way 10 valve 11 through the exhaust 14. The so-called abnormal movement of this wood-feeding instrumentality occurs when the valve 11 is manually turned half-way so that direct connection is had between the port 12 15 of the cylinder and the exhaust 14 to permit escape of the water from the upper portion of the cylinder and to direct the water under pressure from the passage 10 to the port 13 whereby the piston-head 4 is upwardly 20 forced to permit refilling of the pocket with water. This abnormal movement, being substantially unopposed is relatively rapid and demands a relatively increased amount of water.

25 This novel speed-governing means involves the co-operation of two devices which in this preferred embodiment of the invention are disclosed as valve mechanisms. The one mechanism functions principally to increase 30 the friction load upon the grinder whenever the grinder tends to increase its speed of rotation over its desired efficient rate. Such valve mechanism consists broadly of an element rotatively driven by the grinder shaft 35 and adapted to produce fluid pressure on one side of a partitioned chamber, variable in proportion to the speed of rotation of the grinder shaft. This pressure strains to move the partition against, and in an opposite direction to, a straining force exerted on the other side of this chamber partition. This chamber partition may be provided by means of a cylinder and piston structure broadly like the cylinder 3 divided into compartments by the piston 4, but in this preferred form is provided by means of a diaphragm extending across the pressure chamber and connected to a valve, which is movable to control the pressure under which the 45 water is supplied to the pockets through the above-mentioned supply pass. The valve is operatively connected to this diaphragm and is moyed thereby. There is a means straining to move the valve, via the diaphragm, in one direction. Such means is preferably elastic and is here shown as a spring, the straining force of which is preferably adjustable by which means the device may be set for operation to maintain any desired 50 speed of grinder rotation. The grinder-driven rotary element maintains a pressure on the other side of the diaphragm which strains to move the valve in an opposite direction. The variations in the straining pressure, induced by the impeller, function to de-

termine the direction and extent of valve movement which in turn controls the increase or decrease of pressure supplied to the pockets through the water supply pass.

The supply water under pressure enters 70 the valve structure through the port 16 and finds an outlet through the section 17 of the pass. The valve structure includes a pressure chamber 18 provided by the casting 19. The casting 19 is also formed with a central 75 wall 20 which directs the water above and below this wall through the passages 21, into the pressure chamber 18. A substantially annular water-way 22 receives water from the chamber 18 and delivers it to the main 80 section 23 through which the water may travel to the gradually contracted section 15 of the supply pass and thereafter travel to the pipe 9 for delivery to the various passages 10 leading to the cylinders 3 of the pockets 85 7. It may be noted at this point that, as shown in Figure 3, a by-pass is provided around the valve mechanism. This by-pass 25 is provided with pipe-sections suitably coupled and secured to the casting 19 so that 90 water may flow from the port 16 directly to the supply pass on the other side of the valve chamber. The water pressure communicable through this by-pass is variable by means of the manually operable valve 26. The 95 function of this by-pass is to provide a relatively constant flow of water under pressure to the cylinder pistons. This flow is a substantial part of the normal grinding requirement, but only a minor part of the total 100 flow which must be supplied during abnormal refilling movement of the pistons.

For purposes of facility in description, one of the two co-operating valves shown may be termed the upper and the other may be termed the lower valve, although it is to be understood that the valve mechanisms function in other positions.

The upper valve is preferably of the skeleton type and consists of an annular ring portion 27 carried by a plurality of arms or bridges 28 preferably integral with the valve stem 29. Water may, therefore, circulate freely through the valve, finding outlet through the annular opening 30 into the water-way 22 and thence to the supply pass leading to the pockets. A bushing 32 is provided on the casting 19 adjacent the annular opening 30 against which the inner face of this annular valve portion 27 is slidably engageable. This valve is movably mounted to control the pressure under which the water is supplied to the pockets to produce the friction load on the driven grinders. In this preferred construction, the valve is influenced by elastic means straining to move the valve in one direction and by another means actuated by the driven grinder member straining to move the valve in an opposite direction. The elastic means is ad-

105 110 115 120 125 130

- justable to be set at a predetermined point and furnishes a relatively constant straining effort which is opposed by the variable effort of the other means. Several different elastic means 5 may be employed for this purpose and, in this embodiment, it is disclosed as a spring 33 mounted in the frame 34 suitably bolted to the housing. The valve stem 29 upwardly projects and is terminally engaged by a block 35 which substantially forms therewith a ball and socket connection. The lower end of the spring 33 rests upon the opposite face of this block 35 while the upper end of the spring is held by the block 36. 10 This upper block has a substantially ball and socket connection with the threaded bolt 37 adapted to be manually turned, in its threaded engagement with the head 38 of the frames 34, by means of the hand-wheel 39. 15 Upon the rotation of this hand-wheel, the tension of the spring, exerting a downward thrust or spring effort on the valve, may be adjustably varied. 20 The valve, as above noted, is also acted upon by fluid means straining to move the valve in an opposite direction. This fluid means is co-operable with a rotatory element, which is actuated by the driven grinder shaft. The valve stem 29 has a plate 40 secured thereto, the upper face of which abuts against the under face of the diaphragm 41 of suitably flexible material such as a rubber composition. The peripheral portions of this diaphragm are securely held 25 between the chamber housing or casting 46 and the annular plate 42, bolted to the housing. A cap 43 is keyed to the valve stem 29 and is downwardly pressed by means of the adjustable nut 44 received in threaded engagement 30 on the terminal portion of the valve stem 29, securely to hold the diaphragm on the valve stem so that movement of the diaphragm will cause movement of the valve stem. This diaphragm functions as the cover 35 of a pressure chamber 45, the other sides of which are provided by the housing preferably formed by a casting 46 secured by a plurality of bolts 47 to the casting 19 of the 40 waterway housing. 50 This pressure chamber 45 is filled with a fluid such as water, the pressure of which is caused to vary in proportion with the speed of rotation of the grinder shaft, by means 55 of a centrifugal pump type of impeller. This impeller is provided with a housing 50 which upwardly provides a water reservoir 51. The impeller housing is secured to the casting 46 by means of bolts 52. 60 The impeller is provided with a stem 53 rotatably mounted in the housing 50 and having suitably packed bearings to prevent escape of the water. The stem carries a disk 54 bearing radially projecting vanes 55. An annular way within which the disk and 65 vanes rotate is provided by the casting portion 49. A peripheral end portion of the way is provided with an annular passage 56 which, on the side adjacent the pressure chamber 45, communicates with a port 57 leading to the pressure chamber. The function of this impeller is to create pressure. There is merely intermittent, slight flow induced by the impeller as the diaphragm 41 moves up or down between the housing 50 and the pressure chamber 45. Since practically all the energy spent in driving the impeller goes into heat, provision must be made for cooling the circulating medium. This is accomplished by providing small 70 leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 75 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 80 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 85 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 90 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 95 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 100 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 105 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 110 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 115 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 120 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 125 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction 130 is accomplished by providing small leakage passages between the stem 29 and the bearings therefor in the casting 46, so that the water under relatively high pressure in the pressure chamber 18 can escape in sufficient quantity into the pressure chamber 45, and thence through the port 57 into the annular passage 56, and into the overflow reservoir 51, and carry away the heat which may be generated. This construction

crease in speed of the grinder in turn causes the co-operating impeller to rotate at a higher speed and to build up a pressure proportionate to the increased speed in the pressure chamber 45. This increased pressure 5 raises the valve against the tension of the spring 33, so that there is less obstruction to the flow of water from the supply pass to the pistons and hence the pressure on each 10 of the pistons at the pockets is increased and the friction load upon the grinder is thereby increased, and the speed of the grinder thereby reduced to substantially its efficient rate. 15 Provision is made for the accidental interruption of the impeller functions, such as the breaking of the impeller drive, so that the full pressure in the pass is immediately applied to the pistons to place a full friction 20 load upon the grinder to cause its stoppage. Under such conditions this upper valve will assume the position shown in Figure 1 which has been termed an automatic stop position. For example, when the belt 71 25 breaks, the impeller ceases its rotation, pressure drops in the chamber 45, the spring 33 unopposedly exerts its straining effort to cause the valve to descend to the position shown in Figure 1, whereby practically un- 30 impeded flow is permitted through the supply pass.

The structure heretofore referred to can automatically maintain the desired speed of rotation of the driven grinders working 35 under their friction loads produced by the pressure supplied to the pistons under what may be termed normal conditions and also to considerable extent under what may be termed abnormal conditions described later. 40 Each piston has a normal forward movement, under the pressure of the water in the supply pass, forcibly to maintain wood in engagement with the working grinder. This slow piston displacement in the normal 45 maintaining movement causes a relatively small flow of water through the supply pass to the piston cylinders.

However, it is to be noted that each piston also has, what may be termed, abnormal 50 movements. These abnormal movements are attendant upon the manual operation of the valve 11 upon exhaustion of the wood in the pockets, and are to and from the maintaining position. Such movements 55 are necessary in refilling the exhausted pockets. These movements being unopposed, are relatively rapid and entail sudden large flows of water from the supply 60 pass to the cylinders. Such increased flow of water would naturally cause reduction in pressure in the supply pass due to increased friction loss at the higher velocities of flow. The function of the second or lower valve mechanism is to prevent such pressure 65 variation. It effects such result by per-

mitting increased flow of water to the cylinder upon abnormal movement of a piston. Broadly considered, such result is achieved by the application of the Venturi tube principle.

The second or lower valve structure also is mounted for movement to control flow through the fluid pressure pass. It consists of an annular ring portion 73 carried by bridges 74 secured to the valve stem 75. 70 This lower valve is, therefore, similar to the upper valve and likewise water may circulate freely through this skeleton valve. An annular bushing 76 is provided on the casting 19 adjacent the annular opening 30 of the waterway 22. The valve stem 75 is secured by means of its opposed plate 77 to a diaphragm 78. The diaphragm functions as a moving partition in the pressure compartment 79. Movement of the partition is 80 imparted to the valve through the stem 75. This partition is acted upon, and is movable in response to, variations in water pressure on its opposed faces. The motion of this valve is produced by variations in fluid flow 85 through the supply pass, and to this end, the supply pass on the side of the valve structure which is nearer to the pockets is provided with a gradually contracted section 15 through which the water passes from the main section 23 to the section 17 of the supply pass leading to the pipe 9. A passage 81 connects the main section 23 with the pressure compartment 79 on one side of the diaphragm while the passage 82 connects the gradually contracted section 15 with the pressure compartment 79 on the other side of the diaphragm. Therefore, variations in pressure in the passages 81 90 and 82 will cause movement of the valve stem 75. When a pocket is pulled off for refilling, an increased flow of water in the supply pass results and the increased flow of water from the main section 23 through the gradually contracted section 15 results in 95 the transformation of a portion of the fluid pressure head in the main section 23 into fluid velocity head in the contracted section 15, and the attendant drop in pressure in the passage 82 below that in the passage 81 will cause the diaphragm 78 to be downwardly pressed and hence move the valve portion 73 to permit increased volume of water to flow through the pass. Preferably the compartment 79 is provided with a projection 83. A spring 84 is mounted therein and has one 100 terminal portion in engagement with one of the plates 77 of the valve stem. The other terminal portion of the spring is seated on the head of a screw 85 received in threaded 105 engagement in the projection 83. The spring is, therefore, provided with an adjustable mounting so that the upward thrust of the spring on the valve stem may be 110 adjustably altered. A set screw 86 is received 115 in the head of the screw 85. A set screw 86 is received 120 in the head of the screw 85. A set screw 86 is received 125 in the head of the screw 85. A set screw 86 is received 130 in the head of the screw 85.

in threaded engagement at the side of the housing and is adapted to be employed as a stop acting cooperatively with the spring 84 to control the movement of the valve portion in response to any differential in water pressures on the two sides of the diaphragms 78.

Preferably this lower valve structure is provided with a socket 61 which is adapted to receive in sliding engagement a guide-rod 62 provided on the valve stem 29 in axial alignment therewith. This rod and socket device effects a guiding function for the valves which are movable relatively to each other.

There is thus provided an efficient governor which assures the automatic maintenance of a desired speed of rotation of a driven member working under a friction load. While this novel structure is disclosed in its application to wood-pulp grinders in the newsprint paper art, it is to be understood that the construction disclosed herein is illustrative but not restrictive and that the same may be modified within the meaning and scope of the claims which follow.

Having thus described my invention what I claim as new, and desire to secure by Letters Patent, is:

30 1. Means for the automatic maintenance of any desired uniform speed of rotation of a driven member working under a friction load produced by fluid pressure including, a pass adapted to supply fluid under pressure, 35 a valve movable to control the pressure under which said fluid is supplied, a rotatory element actuated by said driven member, and fluid means co-operable with said element to control valve movement whereby said uniform speed of rotation is automatically maintained.

2. Means for the automatic maintenance of any desired uniform speed of rotation of a driven member working under a friction load produced by fluid pressure including, 45 a pass adapted to supply fluid under pressure, a valve movable to control the pressure under which said fluid is supplied, elastic means straining to move said valve in one direction, a rotatory element actuated by said driven member, and fluid means co-operable with said element straining to move said valve in the opposite direction whereby said uniform speed of rotation is automatically maintained.

3. Means for the automatic maintenance of any desired uniform speed of rotation of a driven member working under a friction load produced by fluid pressure including, 60 a pass adapted to supply fluid under pressure, a valve movable to control the pressure under which said fluid is supplied, elastic means straining to move said valve in one direction, means for adjusting the elastic means whereby the straining effort of said

elastic means to move the valve in such direction is adjustably altered, a rotatory element actuated by said driven member, and fluid means co-operable with said element straining to move said valve in the opposite direction whereby said uniform speed of rotation is automatically maintained.

4. Means for the automatic maintenance of any desired uniform speed of rotation of a driven member working under a friction load produced by fluid pressure including, a pass adapted to supply fluid under pressure, a valve movable to control the pressure under which said fluid is supplied, elastic means straining to move said valve in one direction, fluid means straining to move said valve in an opposite direction, and a rotatory element actuated by said driven member and adapted to vary the straining effort of said fluid means in proportion to the speed of rotation of said driven member whereby said uniform speed of rotation is automatically maintained.

5. Means for the automatic maintenance of any desired uniform speed of rotation of a driven member working under a friction load produced by fluid pressure including, a pass adapted to supply fluid under pressure, a valve movable to control the pressure under which said fluid is supplied, elastic means straining to move said valve in one direction, fluid means straining to move said valve in an opposite direction, a pressure chamber for said fluid means, means on said valve projecting into said pressure chamber whereby variations in the straining effort of said fluid means in said chamber produce valve movement in said opposite direction, and a rotatory element actuated by said driven member and adapted to vary the straining effort of said fluid means in said chamber in proportion to the speed of rotation of said driven member whereby said uniform speed of rotation is automatically maintained.

6. Means for the automatic maintenance of any desired uniform speed of rotation of a driven member working under a friction load produced by fluid pressure including, a pass adapted to supply fluid under pressure, a valve movable to control the pressure under which said fluid is supplied, a pressure chamber, a movable partition in said chamber, means connecting said valve with said partition to cause the valve to move therewith, elastic means straining to move said partition in one direction, fluid means straining to move said partition in an opposite direction, and a rotatory element actuated by said driven member and adapted to vary the straining effort of said fluid means in proportion to the speed of rotation of said driven member whereby said uniform speed of rotation is automatically maintained.

7. Means for the automatic maintenance

of a desired speed of rotation of a driven member working under a friction load produced by fluid pressure including, an instrumentality having normal movement 5 forcibly to maintain objects in engagement with said working member and having abnormal movement upon travel to and from maintaining position, a pass adapted to supply fluid under pressure, a valve co-operating with said driven member to control the pressure under which said fluid is supplied to said instrumentality to cause said normal movement thereof, and a second valve operable to permit increased flow of 10 fluid under pressure to the instrumentality, said increased flow being caused by abnormal movement thereof, whereby variations in pressure at said instrumentality which normally would result from variations in 15 fluid flow through said pass are prevented.

8. Means for the automatic maintenance of a desired speed of rotation, of a driven member working under a friction load produced by fluid pressure including, a plurality 25 of instrumentalities each having normal movement forcibly to maintain objects in engagement with said working member and having abnormal movement upon travel to and from maintaining position, a pass adapted to supply fluid under pressure, a valve co-operable with said driven member to control the pressure under which said fluid is supplied to each instrumentality to cause normal movement thereof, and a 30 second valve operable to permit increased flow of fluid under pressure to each instrumentality caused by abnormal movement thereof, whereby variations in pressure which normally would result from variations 35 in fluid flow through said pass are prevented.

9. Means for the automatic maintenance of a desired speed of rotation, of a driven member working under a friction load produced by fluid pressure including, a pass 45 adapted to supply fluid under pressure, a driven shaft, a plurality of rotatably driven working members on said shaft, a plurality of instrumentalities for each driven working member, each instrumentality having normal movement forcibly to maintain objects in engagement with said working member, and having abnormal movement upon travel to and from maintaining position, a 50 valve co-operable with said driven shaft to control the pressure under which said fluid is supplied to each of said instrumentalities to cause normal movements thereof, and a second valve operable to permit increased 55 flow of fluid under pressure to any instrumentality caused by abnormal movement thereof, whereby variations in pressure which would normally result from variations 60 in fluid flow through said pass are prevented.

10. Means for the automatic maintenance of a desired speed of rotation of a driven member working under a friction load produced by fluid pressure, including, a pass adapted to supply fluid under pressure, a valve movable to control the pressure under which 65 said fluid is supplied, said pass having a main section and a gradually contracted section adapted to transform a portion of the fluid pressure into fluid velocity, a pressure compartment, a movable partition 70 therein, a passage connecting the contracted section and the compartment on one side of the partition, a passage connecting the main section and the compartment on the other side of the partition, and means connecting 75 said partition to the valve whereby motion of said valve is produced by variations in fluid flow through said supply pass.

11. Means for the automatic maintenance of a desired speed of rotation of a driven member working under a friction load produced by fluid pressure, including, a pass adapted to supply fluid under pressure, a valve movable to control the pressure under 80 which said fluid is supplied, said pass having a main section and a gradually contracted section adapted to transform a portion of the fluid pressure head into fluid velocity head, a pressure compartment, a movable partition therein, a passage connecting the contracted section and the compartment on one side of the partition, a passage connecting the main section and the compartment on the other side of the partition, means connecting said partition 85 to the valve whereby motion of said valve is produced by variations in fluid flow through said supply pass, and means to adjust the movement of said valve.

12. Means for the automatic maintenance of a desired speed of rotation of a driven member working under a friction load produced by fluid pressure, including, a pass adapted to supply fluid under pressure, means actuated by the rotation of the driven member to control pressure in said pass, and a complementary means actuated by fluid flow through said pass to control the 90 pressure therein.

13. Means for the automatic maintenance of a desired speed of rotation of a driven member working under a friction load produced by fluid pressure including, a two-part supply of fluid under pressure to produce said load, a by-pass to supply one part thereof, and a pass to supply the other part, and means automatically to control the part supplied through said pass proportionately to the speed of rotation of said driven member.

14. Means for the automatic maintenance of a desired speed of rotation of a driven member working under a friction load pro-

- duced by fluid pressure including, a two-part supply of fluid under pressure to produce said load, a by-pass to supply a substantially constant part thereof, and a pass 5 to supply variably the other part thereof, and means automatically to vary the part supplied through said pass proportionately to the speed of rotation of said driven member.
- 10 15. Means for the automatic maintenance of any desired uniform speed of rotation, of a driven member working under a friction load produced by fluid pressure including, a two-part supply of fluid under pressure 15 to produce said load, a by-pass to supply one part thereof, and a pass to supply the other part, and means automatically to control the part supplied through said pass so as to maintain any desired speed of rotation of the driven member.
16. Means for the automatic maintenance of any desired uniform speed of rotation, of a driven member working under a friction load produced by fluid pressure, including, 20 a pass adapted to supply fluid under pressure, a valve movable to control the pressure under which said fluid is supplied, elastic means straining to move said valve in one direction, a rotatory element actuated 25 by said driven member, fluid means co-operable with said element straining to move said valve in the opposite direction, whereby said uniform speed of rotation is automatically maintained, and said elastic means 30 being adapted upon non-actuation of said rotatory element to move the valve to pass- 35 opening position whereby rotation of the driven member is stopped.
17. Means for the automatic maintenance of a desired speed of rotation of a driven member working under a friction load produced by fluid pressure including, an instrumentality having normal movement forcibly to maintain objects in engagement with said working member and having abnormal movement upon travel to and from maintaining position, a pass adapted to supply fluid under pressure, a valve co-operating with said driven member to control the pressure under which said fluid is supplied to said instrumentality to cause said normal movement thereof, and a second valve operable to permit increased flow of fluid under pressure to the instrumentality, said pass having a portion shaped to provide a Venturi tube, a pressure chamber, a partition movable in said chamber and connected to said second valve, passages leading to the pressure chamber at opposite sides of the partition and from different portions of the 40 Venturi tube whereby said second valve operates to permit increased flow of fluid under pressure to the instrumentality upon abnormal movement of said instrumentality whereby variations in pressure at said instrumentality which normally would result from variations in fluid flow through said pass are prevented.
18. In witness whereof, I have hereunto set my hand this 17th day of March 1920.
- ADOLPH F. MEYER.
